UNITED STATES PATENT OFFICE.

EDGAR L. HULL, OF WALTHAM, MASSACHUSETTS, ASSIGNOR TO THE
AMERICAN WALTHAM WATCH COMPANY, OF SAME PLACE.

DESIGN FOR A SERIES OF TIME-PIECE CHARACTERS.

SPECIFICATION forming part of Design No. 17,357, dated May 24, 1887.

Application filed June 1, 1886. Serial No. 203,841. Term of patent 14 years.

To all whom it may concern:

Be it known that I, EDGAR L. HULL, of Waltham, in the county of Middlesex and State of Massachusetts, have invented a new 5 and original Design for a Series of Time-Piece Characters, of which the following is a specification.

My design has reference to time-dial characters; and it consists, as set forth in the accompanying drawings, of a series of characters comprising each the representation of a numeral or figure of the ordinary Arabic notation interlocked with a numeral or figure of the Roman notation.

15 In the accompanying drawings the figures ranging from 1 to 12 are represented in the form of the Roman notation, while the interlocking figures, ranging from 13 to 24, are represented as in the form of the Arabic notation.

The leading feature of my design is, therefore, 20 the hybrid character comprised in the series of these figures interlocked and monogrammed, as shown.

I claim—

The design for a series of time-dial characters, as shown and described, the same consisting of a series of numerals of the Roman notation interlocked with the series of numerals of the Arabic notation, as specified.

In testimony whereof I have signed my name 30 to this specification, in the presence of two subscribing witnesses, this 24th day of May, A. D. 1886.

EDGAR L. HULL.

Witnesses:

W. F. HARRINGTON,
L. M. KNIGHT.
